MULTIPLE GLASS SASH

Christian M. Verhagen, Elkhart, Ind., assignor to
The Adlake Company, Chicago, Ill., a corpora-
tion of Illinois

Application August 1, 1941, Serial No. 405,052

7 Claims. (Cl. 189—64)

The purpose of this invention is to provide a double glass sash of improved construction which is comparatively inexpensive to manufacture, is easy to put together and take apart, effectively seals the edges of the panes of glass, and prevents any appreciable conduction of heat from one side of the sash to the other.

While the foregoing statements are indicative in a general way of the nature of the invention, other more specific objects and advantages will be evident to those skilled in the art upon a full understanding of the improved sash construction.

A preferred embodiment of the invention is presented herein for the purpose of exemplification, but it will of course be appreciated that the invention is susceptible of being incorporated in other structurally modified forms coming equally within the scope of the appended claims.

In the accompanying drawing:

Fig. 1 is a perspective view of one corner of a double glass sash constructed in accordance with the invention;

Fig. 2 is a transverse section through one of the rails of the sash, taken on the line 2—2 of Fig. 1; and

Fig. 3 is a separated perspective view showing short sections of the several parts in unassembled condition.

The particular sash shown in the drawing is provided with two panes 10 and 11 of glass, but it will of course be understood that the sash features hereinafter described are equally applicable to constructions employing more than two panes of glass.

The sash rails are each characterized by a 35 center strip 12 of rectangular cross section. The strip 12 serves as an insulator in the assembly and may be composed of any suitable insulating material, such as hard rubber, hard fiber, or the like. The sash rails are each also characterized by a pair of side plates 13 and 14 which are located at opposite sides of the center strip 12. These side plates may advantageously be of extruded aluminum construction.

The side plate 13 is provided at its outer edge with a thin rib 15 which extends laterally into engagement with the center strip 12 at the outer edge of the latter, and is provided intermediate its inner and outer edges with a relatively thick rib 16 which likewise projects into engagement with the center strip 12 adjacent the inner edge of the latter. The channel resulting from the provision of the ribs 15 and 16 constitutes an air chamber 17 which is closed off by the adjacent face of the center strip 12. The side plate 14 is

provided with corresponding ribs 18 and 19 and a corresponding air chamber 20.

The above described parts are clamped securely together by screws 21 which pass through apertures in the center plate 12 and engage within threaded apertures in the rib 16 of the side plate 13. The side plates 13 and 14 are joined integrally or in any other way at their ends with similar side plates, to complete the rectangular form of the sash.

The edges of the panes 10 and 11 are mounted in grooves 22 and 23 formed in a glazing strip 24. The glazing strip 24 is made of soft rubber and is positioned between the inner portions 25 and 15 26 of the side plates 13 and 14, in abutment with the adjacent edge of the center strip 12 and the adjacent faces of the ribs 16 and 19. The glazing strip 24 when uncompressed is somewhat wider than the distance between the inner portions 25 and 26 of the side plates, with the result that when the side plates are clamped tightly together on the center strip 12 by the screws 21 the glazing strip will be compressed tightly against both panes to space them apart and at the same time effectively seal them.

With this improved sash construction the parts 12, 13 and 14 can be easily and quickly separated from each other, to install or remove either or both of the panes of glass, and when the parts 30 are assembled, as shown in Fig. 2, the panes will be fixedly secured in position and conduction of heat from one side of the sash to the other will be almost entirely eliminated.

I claim:

1. In a sash, a pair of metal side plates provided with confronting ribs adjacent their outer edges and other confronting ribs intermediate their inner and outer edges, an insulating strip positioned between the side plates in engagement with the ribs, a resiliently compressible glazing strip clamped between the inner edges of the side plates inwardly of the inner edge of the insulating strip, two or more spaced panes of glass supported by the glazing strip, and means 40 for clamping the side plates against the insulating strip with the glazing strip compressed between the inner edges of the side plates by the action of said clamping means.

2. In a sash, a pair of metal side plates, an insulating strip positioned between the outer portions of the side plates in engagement with the latter, a resiliently compressible glazing strip clamped between the inner portions of the side plates adjacent the inner edge of the insulating strip, two or more spaced panes of glass separated

by the glazing strip, said insulating strip solidly abutting the side plates at points adjacent both the outer and inner edges of the insulating strip, and means intermediate said points for clamping the side plates against the insulating strip with the glazing strip resiliently compressed between the inner edges of the side plates by the action of said clamping means.

3. In a sash, a pair of metal side plates, an insulating strip positioned between the outer portions of the side plates in engagement with the latter, a resiliently compressible glazing strip clamped between the inner portions of the side plates adjacent the inner edge of the insulating strip, two or more spaced panes of glass separated by the glazing strip, said insulating strip solidly abutting the side plates at points adjacent both the outer and inner edges of the insulating strip, and means intermediate said points for clamping the side plates against the insulating strip with the glazing strip resiliently compressed between the inner edges of the side plates by the action of said clamping means, said clamping means consisting of screws which extend through apertures in one of the side plates and apertures in the insulating strip into threaded apertures in the other side plate.

4. In a sash, a pair of metal side plates, an insulating strip positioned between the outer portions of the side plates in engagement with the latter, said side plates forming between the inner portions of the same a single glazing groove wide enough for the accommodation of two or more panes of glass, a resiliently compressible glazing strip clamped in the glazing groove formed between the inner portions of the side plates inwardly of the inner edge of the insulating strip, two or more spaced panes of glass mounted in and separated by the glazing strip, and means for clamping the side plates solidly against the insulating strip with the glazing strip resiliently compressed between the inner edges of the side plates by the action of said clamping means.

5. In a sash, a pair of metal side plates, an insulating strip positioned between the outer portions of the side plates in engagement with the latter, said side plates forming between the inner portions of the same a single glazing groove wide enough for the accommodation of two or more panes of glass, a resiliently compressible glazing strip clamped in the glazing groove formed between the inner portions of the side plates inwardly of the inner edge of the insulating strip, two or more spaced panes of glass mounted in

and separated by the glazing strip, and means for clamping the side plates solidly against the insulating strip with the glazing strip resiliently compressed between the inner edges of the side plates by the action of said clamping means, the outer edge of said insulating strip being substantially flush with the outer edges of the side plates, and forming with the side plates a single self-contained sash rail of substantially rectangular cross section.

10 6. In a sash, a pair of metal side plates, an insulating strip positioned between the outer portions of the side plates in engagement with the latter, said side plates forming between the inner portions of the same a single glazing groove wide enough for the accommodation of two or more panes of glass, a resiliently compressible glazing strip clamped in the glazing groove formed between the inner portions of the side plates inwardly of the inner edge of the insulating strip, two or more spaced panes of glass mounted in and separated by the glazing strip, and means for clamping the side plates solidly against the insulating strip with the glazing strip resiliently compressed between the inner edges of the side plates by the action of said clamping means, said insulating strip solidly abutting the side plates at points adjacent the outer and inner edges respectively of the insulating strip, and said side plates being recessed away from the insulating strip intermediate the points of abutment.

20 7. In a sash, a pair of metal side plates, an insulating strip positioned between the outer portions of the side plates in engagement with the latter, said side plates forming between the inner portions of the same a single glazing groove wide enough for the accommodation of two or more panes of glass, a resiliently compressible glazing strip clamped in the glazing groove formed between the inner portions of the side plates inwardly of the inner edge of the insulating strip, two or more spaced panes of glass mounted in and separated by the glazing strip, and means for clamping the side plates solidly against the insulating strip with the glazing strip resiliently compressed between the inner edges of the side plates by the action of said clamping means, said insulating strip solidly abutting the side plates at points adjacent the outer and inner edges respectively of the insulating strip, and one or more of said abutting members being recessed away from the other intermediate the points of abutment.

CHRISTIAN M. VERHAGEN.
